EXPLOSION-TURBINE.

1,109,643.

Specification of Letters Patent.

Patented Sept. 1, 1914.

Application filed June 7, 1913. Serial No. 772,332.

To all whom it may concern:

Be it known that I, FRANZ PRETTNER, a subject of the Emperor of Austria-Hungary, residing at Eibiswald, Styria, Austria-Hungary, have invented certain Improvements in Explosion-Turbines, of which the following is a specification.

The present invention relates to an explosion turbine and consists in the various details of construction and combination of parts as hereinafter set forth and claimed, its object being to produce a power generator which is particularly suited for aerial crafts and in which, for that purpose, simplicity and light weight is combined with maximum power output, certainty of function, and complete safety against external explosions.

In the accompanying drawings the invention is illustrated, Figure 1 representing a side view of the machine, partly in section, Fig. 2, a view of part of the rotor and its casing in diametral section, Fig. 3, a top view of the casing containing the compression and combustion cylinders, Fig. 4, a cross-sectional view of one of the pistons fitted in the combustion cylinders, Fig. 5, an edge view of the rotor casing, partly in section, Fig. 6, a view, partly in section on an enlarged scale, of the compression and combustion cylinders with their appurtenances, and Fig. 7, a longitudinal section of one of the piston rods.

The rotor wheel 1 is inclosed in a casing 2 which communicates with two combustion chambers 3 arranged in juxtaposition. The explosions occur alternately in the two chambers, and the nozzles 4, which are arranged for radial flow, direct the fluid to the rotor at opposite sides of a central ring 5 which projects beyond the blades and which takes, with its projecting part, into a groove made in the rotor casing (Figs. 2 and 5). The action of each nozzle is thus strictly confined to a separate portion of the rotor.

A spring-actuated piston 6 is so arranged in each combustion chamber as to normally protect the nozzle, the piston being itself hollow and open-ended, as shown in Fig. 4, so as not to be effected by the explosion. The piston may be solid, in which case the ends of the cylinder are set into communication by means of pipes or ducts. Sparking elements 7 are fitted in the chamber wall 50 so as to be normally in touch with a con-

tact piece 8 connected to the piston rod 9 within the chamber, the conductor from said contact piece being led through the rod to the outside and embedded in an insulation 10, as shown in Fig. 7.

The casing containing the two combustion chambers is integral with the compression cylinder 11 the opposite ends of which communicate with the combustion chambers, one with each through the medium of pipes 12 and check valves 13. A piston 14 is arranged in the compressor cylinder so as to force air into one combustion chamber during the forward, and into the other during the return stroke. The compressor piston is reciprocated by means of a crank-shaft 15 rotation to which is communicated, for instance by means of a chain gearing 16, from the turbine shaft 17. Tappets or cams 18 are mounted on the crank-shaft so as to contact with the levers 19, pivoted at 20, for displacing the pistons in the combustion chambers, in opposition to springs 21 and setting said chambers in communication with the rotor casing. This is effected when the compressor piston has traveled through 4/5ths of its stroke. Simultaneously with the displacement of the piston in the combustion chamber the circuit of the sparking elements is interrupted and a spark produced for exploding the compressed fluid. The fuel is fed into the combustion chambers by means of a pump 22 which is also double-acting and which pumps said fuel, at each stroke, from a reservoir 23 into the same combustion chamber as is being fed with air. The pump is driven by an eccentric or a crank 24 mounted on the crank-shaft 15 and through the medium of a Stephenson link 25. The position of the pump rod relative to said link is controlled by a centrifugal governor 26 which is driven by the turbine shaft 17, the fuel supply being thereby regulated.

The spent gases are discharged from the turbine casing through an exhaust port in the usual manner. The spokes of the rotor wheel are fitted with fans 27 which circulate air successively through cooling jackets 28 arranged about the turbine casing, and similar jackets arranged about the combustion chambers and the compressor cylinder. The air enters the turbine casing through apertures 29 (Fig. 1) made in the side wall around the shaft, and is passed

into the cooling jacket 28 at the upper part of the casing.

In the case of small turbines the starting is effected by a simple starting handle. 5 Larger turbines are started by means of air which is compressed into a metal bottle 30 at about 60 atmospheres. The bottle is restored to normal pressure, after each starting, by means of the compressor which communicates therewith through a narrow pipe 31. A large pipe 32 connects the bottle with the rotor casing. Both pipes are fitted with suitable valves.

I claim:—

15 1. An explosion turbine comprising in combination, a rotor casing, a rotor wheel arranged in said casing and provided with a central circumferential ring, the rotor casing having a groove in which to accommodate said ring, two cylindrical combustion chambers arranged in juxtaposition and connected to the rotor casing so as to direct the motive fluid radially to the rotor at opposite sides of said ring, an air pump driven by the rotor for forcing air alternately into the combustion chamber, means actuated by the pump shaft for feeding motive fluid into said chambers simultaneously with the air, spring-actuated pistons arranged in the combustion chambers so as to close normally the communication with the rotor casing, 80 cams on the pump shaft for operating the pistons and opening said communication at the moment of explosion, sparking elements arranged in the combustion chambers so as to be normally in contact, one element being connected to the piston rod so as to interrupt the contact and produce the spark when the piston is actuated in opposition to its spring, the electric conductor to said latter element being carried through the piston rod to the outside.

2. An explosion turbine comprising in combination, a rotor casing, a rotor wheel arranged in said casing and provided with a central circumferential ring, the rotor casing having a groove in which to accommodate said ring, two cylindrical combustion chambers arranged in juxtaposition and connected to the rotor casing so as to direct the motive fluid radially to the rotor at opposite sides of said ring, an air pump driven by the rotor for forcing air alternately into the combustion chambers, the casing containing the combustion chambers being integral with the pump cylinder, means actuated by the pump shaft for feeding motive fluid into said chambers simultaneously with the air, spring-actuated pistons arranged in the combustion chambers so as to close normally the communication with the rotor casing, 110 cams on the pump shaft for operating the pistons and opening said communication at the moment of explosion, and means operated by the piston rods for igniting the explosive mixture.

55 3. An explosion turbine comprising in combination, a rotor casing, a rotor wheel arranged in the combustion chambers so as to close normally the communication with the rotor casing, cams on the pump shaft for operating the pistons and opening said communication at the moment of explosion, and means operated by the piston rods for igniting the explosive mixture, and means operated by the rotor shaft regulating the fuel supply.

60 4. An explosion turbine comprising in combination, a rotor casing, a rotor wheel arranged in said casing, two cylindrical combustion chambers arranged in juxtaposition and connected to the rotor casing so as to direct the motive fluid radially to the rotor, an air pump driven by the rotor for feeding air alternately into the combustion chambers, means actuated by the pump shaft for feeding motive fluid into said chambers

120 arranged in said casing and provided with a central circumferential ring, the rotor casing having a groove in which to accommodate said ring, two cylindrical combustion chambers arranged in juxtaposition and connected to the rotor casing so as to direct the motive fluid radially to the rotor at opposite sides of said ring, an air pump driven by the rotor for forcing air alternately into the combustion chambers, means actuated by the pump shaft for feeding motive fluid into said chambers simultaneously with the air, spring-actuated pistons arranged in the combustion chambers so as to close normally the communication with the rotor casing, 85 cams on the pump shaft for operating the pistons and opening said communication at the moment of explosion, sparking elements arranged in the combustion chambers so as to be normally in contact, one element being connected to the piston rod so as to interrupt the contact and produce the spark when the piston is actuated in opposition to its spring, the electric conductor to said latter element being carried through the piston rod to the outside.

4. An explosion turbine comprising in combination, a rotor casing, a rotor wheel arranged in said casing and provided with a central circumferential ring, the rotor casing having a groove in which to accommodate said ring, two cylindrical combustion chambers arranged in juxtaposition and connected to the rotor casing so as to direct the motive fluid radially to the rotor at 100 opposite sides of said ring, an air pump driven by the rotor for forcing air alternately into the combustion chambers, a double-acting fuel pump adapted to feed fuel alternately into the two combustion chambers simultaneously with the air, connections, including a crank and a Stephenson link, between the air pump shaft and the fuel pump rod for operating the latter, a centrifugal governor driven by the rotor shaft and connected to said Stephenson link for regulating the fuel supply, spring-actuated pistons arranged in the combustion chambers so as to close normally the communication with the rotor casing, 115 cams on the pump shaft for operating the pistons and opening said communication at the moment of explosion, and means operated by the piston rods for igniting the explosive mixture.

5. An explosion turbine, comprising in combination, a rotor casing, a rotor wheel arranged in said casing, two cylindrical combustion chambers arranged in juxtaposition and connected to the rotor casing so as to direct the motive fluid radially to the rotor, an air pump driven by the rotor for feeding air alternately into the combustion chambers, means actuated by the pump shaft for feeding motive fluid into said chambers

simultaneously with the air, means for igniting the explosive mixture in the combustion chamber, means for putting said combustion chambers into communication with the rotor casing at the moment of explosion, a metal bottle adapted to hold compressed air, means for setting said bottle into communication with the rotor casing for start-

ing the rotor and means for setting the bottle into communication with the air pump 10 for restoring the bottle to normal pressure after such starting.
